UNITED STATES PATENT OFFICE.

INEZ MERCY FOSTER, OF SIMLA, INDIA.

NOVELTY HOLDER.

Application filed February 20, 1926. Serial No. 89,803, and in Great Britain February 26, 1925.

My present invention has reference to what I will term a novelty holder.

My object is the provision of a device having a compartment in which is arranged a receptacle that contains toys, novelties or any other desired objects, and which is normally concealed in the compartment through the medium of doors or closures for the said compartments, and which, when the said doors or closures are opened, is automatically projected a determined distance through the compartment, so that the contents of the receptacle will be exposed and may be removed therefrom.

A further object is the provision of a novelty of this character adapted to serve as a dispenser for gifts, especially at Christmas time, and which will serve both as an amusement and surprise for children as well as adults.

A still further object is the provision of a novelty of this character having doors closing a compartment, and in which compartment there is arranged a receptacle for suitable articles to be dispensed as Christmas presents and wherein means is provided for swinging the doors or closures to open position and for elevating the receptacle to bring the contents of the latter to display position, means being also provided whereby the closing of the doors will cause the receptacle to travel to its initial position, while a musical instrument will be operated in the sliding of the receptacle to both of its positions.

A still further object is the provision of a novelty of this character which will serve as a storage for perishable articles, and which while primarily designed as a container for Christmas gifts or favors may be also employed as a display and dispensing device for commercial articles.

To the attainment of the above broadly stated objects and many others which will appear as the nature of the invention is better understood, reference is to be had to the drawings in which there are illustrated satisfactory embodiments of the invention, and wherein:

Figure 1 is an approximately central longitudinal sectional view through the improvement.

Figure 2 is a sectional view on the line 2-2 of Figure 1.

Figure 3 is a sectional view on the line 3-3 of Figure 1.

Figure 4 is a perspective view of the slideable frame for the shiftable gears.

Figure 5 is a sectional view on the line 5-5 of Figure 1.

Figure 6 is an enlarged detail sectional view of the operating handle for the gear shift.

In these figures a cylindrical compartment is indicated by the numeral 26 and the slideable gift or toy holding receptacle by 27. Two doors are provided for the compartment 26. These door sections are each indicated by the numeral 28, each of the said sections being hinged, as at 29, to the mouth of the compartment. Inward of the hinges there is fixedly secured in the compartment plates 30 whose outer ends are preferably rounded and bifurcated. Passing through the headed ends of the arms there are pivots 31 which secure therebetween the rounded and headed ends of curved arms 33. The heads 32 are peripherally toothed and the outer ends of the arms have pivotally secured thereto anti-frictional rollers 34. These rollers normally contact

with the inner rounded faces of the cover sections 28 and are held in such engagement by track members 35. The plates 30 may have their inner fixed ends extended to provide substantially U-shaped brackets 36, and journaled through these brackets and the walls of the compartment 26 there are short stub shafts 37. Fixedly secured on each of the stub shafts 37 there is a worm wheel 38 that is in mesh with the toothed head 32 of the respective arms 33. The stub shafts also support thereon sprocket wheels 39 around which are trained sprocket chains 40. These chains are also trained around similar sprocket wheels that are fixed on a shaft 41 whose ends are journaled in bearings on the inner side of the compartment 26 below the bottom of the receptacle 27. The shaft 41 has fixed thereon, equidistant from its center facing beveled gears 42 and 43, respectively.

The receptacle 27 is held properly spaced from the compartment 26 through the medium of curved arms or levers 44 supported by means 45 on the bottom of the receptacle 27. The portions of the arms depending below the supports 45 are of a materially greater length than those projecting upwardly from said supports, and each end of the curved arms is bifurcated and has

105
110

pivottally mounted therein anti-frictional will contact with the lugs 77 and elevate the rollers 46 and 47, respectively. These rollers contact with the inner walls of the compartment 26.

Disposed centrally between the facing beveled gears 42 and 43 and suitably supported on the bottom of the compartment 26 there is a spring wound motor 48. The barrel of the motor has centrally secured thereon a ring gear 49 which is in mesh with a similar ring gear 50 that is mounted on a shaft 51 and the flat upper face of the ring gear may provide a table for a disc record 52. The record has its groove engaged by the lever on the sound arm of a phonograph 53.

The spring wound motor 48 is provided with a winding gear 54 engaged by a pinion 55 that carries a gear 56. The gear 56 is in mesh with a gear 57 on the end of a winding rod or lever 58. The lever is journaled in suitable bearings and passes through one side of the compartment and has its outer end cranked, as at 59.

On its upper face the motor casing is provided with a beveled gear 60 which is, of course, operated by the motor and this gear is at all times in mesh with two oppositely disposed comparatively small beveled gears 61 and 62 which have stub shafts journaled in bearings in suitable uprights that are fixed in the bottom or floor of the compartment. To the opposite sides of the motor 48 there are secured on the floor or bottom of the compartment 26 the foot portions of frame members 63. The upper portion of the frame members are each provided with spaced longitudinally extending elongated slots 64 and 65, respectively, and in these slots there are received the rounded ends or lugs 66 formed on upper and lower crossed arms 67 and 68. The edges of one pair of each of the crossed arms have integrally formed therewith U-shaped extensions 69, connected together at their outer end, by a central element 70. Secured to the element 70 there is a rod 71, that passes through a suitable opening 73 in one side of the compartment and which arm has its outer end formed with an arm 74. There is journaled between the central and connecting portions of the crossed arms 67 and 68 a shaft that carries thereon a beveled face gear 75. It will be apparent that by sliding the gear supporting frame, comprising the crossed arms, in one direction the double faced gear 75 will be brought in mesh with the gear 42 and 61 so that the shaft 41 will be turned in one direction. On each of the sprocket chains 40 there is an outstanding lug 76 designed for contacting engagement with similar lugs 77 on the outer face and adjacent to the bottom of the receptacle 27. We will say that the double faced beveled gear when brought to position just described will cause the shaft 41 to revolve so that the lugs 76

will contact with the lugs 77 and elevate the receptacle 27. It is to be noted that the short or stub shafts 37 will be turned by the sprocket chains so that the worm wheels thereon will revolve the pivot arms 33 causing the said arms to swing the cover sections 28 to open position. The swinging movement of the cover sections is limited by the contacting engagement thereof with the outer ends of the stub shafts 37 and when so arranged and the receptacle is brought to its fully elevated position, the lugs 76 will free themselves from engagement with the lugs 77. When so arranged the operator moves the rod 71 to bring the double faced gear 75 out of mesh with the gears 42 and 61 and when it is desired to return the parts to their lowered initial position the rod 71 is further moved so that the double faced gear 75 will be brought to mesh with the gears 43 and 62, thus causing the shaft 41 to turn in a reverse direction and by virtue of such turning to again bring the lugs 76 on the sprocket chain to contact with the lugs 77 to lower the receptacle 27 and to close the covers 28. In the meantime the sound producing device will be operated. Suitable means, broadly indicated by the numeral 79, may be moved to engage one of the gears of the motor to prevent the operation of the member when the receptacle is to be held stationary in the compartment. The rod 71 is provided with spaced spring catches 80 and 81, respectively, These catches are movable to contact with the inner or outer faces of the compartment so that it is not necessary to hold the rod and the gear shift frame associated therewith when the receptacle is being raised or lowered.

It is believed that the foregoing description when carefully read in connection with the drawings will fully set forth the simplicity of my construction, the operation thereof and its many advantages. While I have illustrated satisfactory embodiments of my improved device my features of invention are capable of extended application and I do not wish to be limited to the specific structure herein shown and described.

Having described the invention, I claim:

1. In a device for the purpose set forth, a compartment, hinged doors normally closing the compartment, pivottally mounted arms in the compartment contacting with the doors, and said arms having segmental teeth at their pivoted ends, worm wheels journaled in the compartment and in mesh with said teeth, a receptacle in the compartment, and motor operated means for imparting a vertical movement to the receptacle and for turning the worms to swing the arms to cause the doors to open and close when the receptacle is being raised or lowered.

2. In a device for the purpose set forth, a compartment, hinged doors for closing the compartment, curved arms pivoted in the compartment and having segmental ends formed with teeth, anti-frictional elements on the outer ends of the arms, guide means on the doors for the arms, worm wheels journaled in the compartment and engaging with the toothed ends of the arms, a receptacle in the compartment and motor operated means for raising and lowering the receptacle to predetermined positions in the compartment and for revolving the worm wheels to swing the arms to open or close the doors.

3. In a device for the purpose set forth, a compartment, hinged doors for the compartment, pivotally supported toothed arms in the compartment contacting with the doors, guide means between the arms and doors, worm wheels having shafts journaled in the compartments and in mesh with the toothed portions of the arms, a receptacle arranged for slidable movement in the compartment, a motor, endless chains operated by the motor, and connected with the pivots of the worm wheels for likewise revolving said worm wheels, lugs on the chains, lugs on the receptacle engageable with the lugs of the chains and ridable thereover but de-

signed when contacting therewith to raise

or lower the receptacle and control means for the motor.

4. In a device for the purpose set forth, a compartment, hinged doors for closing the compartment, curved arms having toothed ends supported in the compartment, and engaging with the doors, guide means between the arms and doors, worm wheels having shafts journaled in the compartment and meshing with the toothed portions of the arms, a receptacle arranged for slidable movement in the compartment, means supporting the receptacle in its lower position, anti-frictional means carried by the receptacle and engaging with the compartment, for spacing the receptacle in the compartment, a motor, sprocket chains operated by the motor and connected to the shafts for the worm wheels, means operable from the exterior of the compartment, engageable with the motor and with the drive shaft for the chains to cause the motor to drive the chains in either of two directions or to permit of the operation of the motor without influencing the chains, lugs on the chains, and lugs on the receptacle engageable with the lugs of the chains, as and for the purpose set forth.

In testimony whereof I affix my signature.

INEZ MERCY FOSTER.
